SCRAPER AND EARTH MOVER

Max M. Brodersen, Alhambra, and Len O. Bird, Glendale, Calif., assignors, by direct and mesne assignments, to R. G. Le Tourneau, Inc., Stockton, Calif., a corporation of California

Original application April 6, 1936, Serial No. 72,934. Divided and this application June 7, 1939, Serial No. 277,950

1 Claim. (Cl. 37—126)

This invention relates to improvements in heavy duty earth handling or scraper apparatus of the type shown in our applications for Letters Patent filed March 25, 1935, Serial No. 12,812, Pat. No. 2,168,318, and April 6, 1936, Serial No. 72,934, Pat. No. 2,168,319, the present application being a division of our application Serial No. 72,934.

One of the purposes of this invention is to provide an implement having a bowl and an apron or closure therefor, in which the bowl comprises a forward section which is fixed to the frame and rear section hinged to the forward section whereby the material carried by means of the bowl and apron may be said to be divided into three portions, namely, a portion retained by the apron, a portion retained by the fixed section and a portion in the rear section, thus the portion retained by the apron is discharged upon raising said apron, then, by tilting the rear section, the portion within the forward section is pushed out by the weight of the discharging portion from the rear section and inasmuch as it is necessary to lift only the portion of the material within the rear section of the bowl, less power is required than heretofore possible for handling like loads.

Moreover these provisions in making it unnecessary to lift but one of three portions of the entire load, and but a small part of the load carrying receptacle, decrease friction and wear, render the operation of the implement smoother and more reliable, and also make possible a nicety of control not heretofore possible, as well as increase the efficiency of the implement as a whole.

Another purpose of this invention is to provide heavy duty earth handling apparatus of the character described which by reason of the use of sectional bowl construction and associated means including a scraper blade fixed to the fixed section of the bowl and hinged to the tiltable section of the bowl, makes it unnecessary to employ a latch for holding the tiltable section against undesirable tilting when engaged in the earth during the loading operation.

A further purpose of this invention is to provide apparatus of the character described wherein a novel form of single cable and straight line operated block and tackle means may be advantageously used for controlling and effecting the operation of the sectional bowl-apron unit, such that upon pulling the cable the apron is first lifted and then the movable section of the bowl is tilted and upon releasing the cable, said section of the bowl returns to carrying position first, and then the apron can be lowered.

With the foregoing and other objects in view, the invention hereof consists in the combination, correlation and construction of parts, elements and features which will be described in the following specification and finally pointed out in the claim hereto appended, it being understood that the apparatus of our invention is subject to modification within the scope of said claim.

Figure 1 is top plan view of one form of scraper embodying the invention.

Figure 2 is a side elevation of Figure 1, showing the implement in the carrying position.

Figure 3 is a side elevation showing the implement in the scraping position.

Figure 4 is a side elevation illustrating the dumping position of the implement.

Figure 5 is a section of line 5—5 in Figure 1.

Figure 6 is a section on the same plane as Figure 5, showing the dumping position of the bowl.

Figure 7 is a detail of the swivel means for supporting the implement on the forward carriage.

Figure 8 is a section on line 8—8 in Figure 6.

In the embodiment of the invention, as shown in the accompanying drawings, a jointed vehicular frame structure 1a is made up of forward and rearward sections 2a and 3a. The forward section 2a includes a transverse member 4a provided with a leg 5a swiveled at 6a on a wheeled carriage 7a. A draft tongue 8a provides for connection of said carriage with a tractor. Rearwardly and downwardly extending arms 9a of the carriage 7a are pivotally connected as at 10a with the rearward section 3a.

As here provided the rearward section 3a of frame 1a—comprises side members 62 which in their fabrication include the solid side plates 63 which are of an inverted triangular shape and are fabricated to make the side members 62 of a tubular or hollow cross section, as illustrated in Figure 8. One leg of each of the triangularly shaped member 62 projects rearwardly and terminates in the extension 64 pivotally supported on the rear axle 11a, of a wheeled carriage 12a, while the other leg projects upwardly.

Interposed between the upwardly projecting legs of the triangular side members 62 and secured thereto is a tubular cross member 20a which carries intermediate its ends a pair of forwardly extending lugs 65 which in turn pivotally support as at 22a, the rear ends of the pair of forwardly extending arms 23a. The forward ends of arms 23a are pivotally supported, as at 26a, on the upper ends of links 25a which in turn are pivotally connected, as at 27a, to the frame section 2a. Interposed between the forward ends

of arms 23a is a pulley block 28a. Another pulley block 19a is mounted between the standards 66 on the frame member 2a. A cable 32a dead ended on the standards 66, as at 67, is reaved between the pulley blocks 28a and 19a and passed over one idler pulley 29a and through swiveled pulley 31a and is then connected to a hoist on a vehicle or tractor in the usual manner. When the cable 32 is pulled, the arms 23a are pushed rearwardly, by reason of the fixed pulley block 19a, thereby swinging the rear section 3a upwardly about the axle 11a, thus raising the rear part of a bowl 70 mounted on the rear section 3a. When the cable 32a is released, the weight of the bowl and frame structure lowers the frame and bowl. Lugs 68 on links 25a abut stops 69 on frame member to limit the height to which the implement may be raised.

The bowl 70 comprises a stationary front section 71 and a tiltable rear section 72. The stationary section 71 comprises side plates 73, fixed to the side members 62, and a blade 74 which is interposed between plates 73 and secured to the bottom edge thereof. The tiltable section 72 of the bowl comprises a bucket 75 which is hinged to the blade 74 as shown at 16. An apron or closure 48a pivotally connected as shown at 50a to frame section 3a through the arms 49a, is provided for the receiving end of the bowl 70 for retaining material in excess of the capacity of the bowl.

Pulley blocks 59a, 60a and 61a are mounted on the back of the tiltable section 72, on the cross member 20a and the apron 48a, respectively. A cable 58a is dead ended on the back of the bowl section 72, as shown at 17, and reaved through pulley blocks 59a and 60a, then passed to pulley block 61a and reaved through it and the pulley block 19a, then passed over another idler pulley 29a and through swiveled pulley 30 and then extended so that it may be connected to a hoist on the tractor or vehicle.

When a pulling force is exerted on the cable 58a a block and tackle effect takes place between pulley blocks 19a and 61a thereby raising the apron 48a which is lighter in weight than the tiltable bowl section 72. When the apron reaches the end of its upward movement as limited by the cross member 20a, further pulling on the cable 58a causes a block and tackle effect between pulley blocks 59a and 60a whereby to tilt the bowl section 72 for dumping. When the cable is released the section 72 and apron 48a gravitate to carrying position shown in Figure 2, the section 72 dropping first and then the apron.

By virtue of this construction of the bowl a portion of the accumulated material is discharged first by raising the apron 48a, then by tilting the bowl section 72 the material in the fixed section 71 of the bowl is pushed out by the discharging portion from the tilted section 72, thus it is necessary to lift only the portion of material within the tiltable section of the bowl and consequently, a like amount of material may be handled

with less expenditure of power than heretofore in the art.

Inasmuch as this type of a scraper will handle a larger amount of dirt it is advisable, due to the increase of the load, to provide antifriction bearings 78 in the swivel support 6a carrying the forward end of frame section 2a on the carriage 1a, as illustrated in Figure 7.

It is important to note that due to the construction of the sectional bowl, and especially the rearwardly slanting front edges of the tiltable section of the bowl, there is not sufficient past center weight to counterbalance the tiltable section when in dumping position. If the front section of the bowl was moved or tilted, or the front edges of the rear or tiltable section were vertical instead of slanted obliquely rearwardly, the bowl would tend to remain in dumping position and would not in all cases freely gravitate to carrying position, and in extreme dumping position the vertical edges would tend to gouge the ground in turning and thereby bend or damage the apparatus.

Furthermore elimination of wear and other advantages of our apparatus may also be ascribed to having the stationary front section of the bowl spaced forwardly at all times from the tiltable rear section of the bowl, it being unnecessary to move the tiltable section into overlapping relation with the stationary section except when dumping the load. Moreover the apron is at all times spaced forwardly of and does not overlap the tiltable section. Thus, the load is divided into three distinct portions located and held respectively in the tiltable section, the fixed section and the apron.

Considering the apron as a part of the bowl, such bowl may be said to comprise three sections wherein the middle section is fixed and the other sections are disposed on opposite sides and contiguous with the fixed sections and are relatively adjustable for carrying and dumping portions of the load as well as for causing the fixed section to carry and dump its share of said load.

We claim:

A scraper including a carrying frame, a bowl mounted on the frame and made up of three load-carrying sections, the central bowl section including side plates fixed to the frame and a scraper blade fixed between said plates, another of such bowl sections being pivoted to swing up and down on an axis to the rear of and adjacent said blade and extending backwardly beyond the rear edges of the side plates of the central bowl section, the third bowl section comprising an apron pivoted for swinging movement away from or toward the front edge of the cutting blade, means to swing the second and third sections on their respective pivots, and means to lower or raise the scraper blade to or from scraping position.

MAX M. BRODERSEN.
